UNITED STATES PATENT OFFICE.

JOHN C. MORRISON, OF SPOKANE, WASHINGTON.

PISTOL.

1,290,292.

Specification of Letters Patent.

Patented Jan. 7, 1919.

Application filed September 13, 1918. Serial No. 253,926.

To all whom it may concern:

Be it known that I, JOHN C. MORRISON, a citizen of the United States, residing at Spokane, in the county of Spokane and State of Washington, have invented new and useful Improvements in Pistols, of which the following is a specification.

My present invention has for its object to provide a pistol embodying a simple and inexpensive appurtenance designed and adapted to provide a considerable distance between the front sight and the rear sight, to guard the hammer lug against possible accident, to render the pistol capable of being smoothly and easily drawn, and to afford a comfortable and steady grip.

To the attainment of the foregoing, the invention consists in the pistol equipped as hereinafter described and definitely claimed.

20 In the accompanying drawings which are hereby made a part hereof:

Figure 1 is a side elevation of a pistol of the revolver type equipped with my novel appurtenance.

25 Fig. 2 is a cross section taken through the frame of the pistol and my novel appurtenance.

Fig. 3 is a rear end elevation of the pistol equipped in accordance with my invention.

30 Similar numerals of reference designate corresponding parts in all of the views of the drawings:

The pistol illustrated is of the revolver type but it is to be understood that my invention is applicable to any type of pistol.

35 In furtherance of my invention I provide in conjunction with the frame 1 and a forward sight 2 on the barrel 3 of the pistol, the appurtenance 4 which rests over and 40 forms a guard to the hammer lug 5 and serves to render the weapon easy to draw and absolutely safe. The said appurtenance is in the form of a bar which extends rearwardly flush with the upper side of the 45 pistol frame and is provided at its rear end

with a rear sight 6. The said bar is fixed at its forward end to the pistol frame and merges at its rear end into a depending portion which, in turn, merges into a forwardly extending upwardly curved portion 7 which 50 is fixed at its forward end to the rear side of the upper portion of the pistol grip 8. The rear sight 6 on the bar is located a great distance in rear of the forward sight which is advantageous inasmuch as it contributes to the accuracy of aim, and the lower forwardly reaching and curved portion of the bar is desirable because it enables the operator to obtain a desirable hold on the grip. It will also be noted that my 60 novel bar permits of the hammer lug being readily retracted when it is desired to cock the pistol.

Notwithstanding the practical advantages ascribed in the foregoing to my novel appurtenance, it will be readily appreciated that the same does not add to the length of the pistol and that it increases the weight of the pistol to a very slight extent.

Having described my invention what I 70 claim and desire to secure by Letters Patent is:

In a pistol, the combination with a barrel having a forward sight, a frame, a grip, and a hammer lug extending upwardly from the 75 rear portion of the frame, of a bar appurtenance comprising an upper portion fixed at its forward end to the frame and extending rearwardly from the frame and above the hammer lug, and provided at its rear 80 end with a rear sight, a depending portion into which the upper portion merges at its rear end, and a forwardly extending and upwardly curved portion into which the depending portion merges at its lower end; 85 the said forwardly extending and upwardly curved portion being fixed at its forward end to the rear side of the frame.

In testimony whereof I affix my signature.

JOHN C. MORRISON.
